DRAWING DIE

Harry Hamilton Richardson, Hamilton, Ontario,
Canada

Application July 3, 1936, Serial No. 88,868

10 Claims. (Cl. 205—25)

My invention relates to improvements in dies for cold drawing steel bars into polygon shapes such as bars or rods of rectangular, square, triangular, hexagonal or octagonal cross-section.

Hitherto in cold drawing steel bars into the above referred to shapes it has been the practice to employ substantially sector shaped dies independently adjustable in a holder or housing by means of screws, wedges, or the like with the result that it is exceedingly difficult to accurately centre the die in the housing. Moreover, when such sector shaped dies become worn it is impossible to resize them for drawing a shape of the same cross-sectional dimensions as it originally drew.

The present invention has for an object to devise a die composed of a number of substantially sector shaped portions so formed as to be capable of insertion into a housing wherein they will be accurately centered thus producing bars of required shapes which are uniform and without fins.

A further object is to devise a die in which when worn the sector shaped portions may be reground and so inserted into the housing and adjusted therein that they will draw a bar of the same cross-sectional dimensions as the die was originally intended for.

A still further object is to devise a die for the above purpose in which the sector shaped portions will lend themselves susceptible to being accurately gauged to ensure their uniformity with other sector shaped portions prior to insertion into the housing.

With the above and other objects which will hereinafter appear as the specification proceeds my invention consists, in its preferred embodiment, of a die constructed and arranged all as hereinafter more particularly described and illustrated in the accompanying drawing in which:—

Fig. 1 represents a side elevation of my die showing the same inserted in a holder of a cold drawing machine.

Fig. 2 is a front view of my die shown from the bar entry side.

Fig. 3 is a vertical cross-section through the line 3—3 (Fig. 2).

Fig. 4 is a similar section showing reground sector portions of the die so disposed in the housing as to draw a bar of the same cross-sectional dimensions as would the die illustrated in Figs. 2 and 3, and

Fig. 5 is a perspective detail drawn to an en-

larged scale showing one of the substantially sector shaped portions of my die.

Like characters of reference indicate corresponding parts in the different views.

As illustrated my die is of a construction suitable for drawing a bar of hexagon cross-section.

My die comprises a housing 1 preferably having a truncated conical exterior 2 for insertion into the truncated conical interior of the die holder 3 of a cold drawing machine. Obviously the housing 1 could, in lieu of the form shown, be so constructed as to be held in the holder 3 in any suitable manner.

The interior 4 of the housing 1 is cylindrical and has a comparatively small axial orifice 5 at one end to receive the drawn bar, its other end being open and of substantially the diameter of the cylindrical interior 4. The interior of the lip of the housing is threaded into which is screwed a retaining ring 6.

A die sector holding ring 7 has a cylindrical exterior 8 of substantially the diameter of the interior 4 of the housing and a truncated conical interior 9, the smaller end of the latter being disposed towards the end of the housing provided with the retaining ring 6, or in other words, towards the bar entering end of the assembled die.

Each die sector portion 10 has its outer arcuate face 11 inclined to correspond with the inclination of the interior 9 of the ring 7 and such arcuate face is ground off intermediately of the ends to give a two point contact on such truncated conical interior 9 of the die sector holding ring 7. The forward end of the bar engaging face 12 of each die sector portion is ground arcuately outward to give a mouth for the reception of the bar to be drawn when the sector portions are assembled.

A circular plate 13 having a circular boss 14, the latter inserted into the orifice 5, is interposed between the die sector portions and the rear wall of the housing 1 and such plate is of such diameter that it may enter the truncated conical interior of the die sector holding ring 7 from the larger end of the latter.

All the parts above referred to are disposed concentrically in the interior 4 of the housing 1.

In assembling the die, the sector portions 10 are assembled in the die sector holding ring 7 with their arcuate faces 11 engaging the truncated conical interior 9 of the ring and their radially disposed surfaces abutting the corresponding surfaces of adjacent die sector portions, the mouth formed by the arcuate forward ends of the faces

12 being directed towards the bar entering end of the die.

The die sector holding ring 7 with the die sectors therein is then inserted into the housing with the 5 larger end of its truncated conical interior 9 directed towards the plate 13 wherein the latter abuts the rear ends of the sectors when the retaining ring 6 is screwed up against the forward face of the ring 7 thus forcing the sectors into intimate 10 contact with each other and with the interior 9 of such ring 7. Consequently the sector die assembly is accurately centred and retained in the housing and bars drawn through the die are uniformly sized.

15 Upon the bar engaging faces 12 of the sectors becoming worn through continual drawing by unscrewing the retaining ring 6 and removing the die sector holding ring 7 with the assembled sectors therein the latter may be removed and 20 reground. When the faces 12 of the sectors have been reground the outer inclined arcuate faces 11 can be ground off commensurately to enable the outer truncated conical periphery of the die sector assembly when replaced in the ring 7 to be disposed a further extent forwardly in the interior 9 of such ring. When the ring 7 with assembled die 25 sectors is replaced in the housing 1 and the retaining ring 6 is again screwed up the plate 13 will enter the interior 9 of the ring 7 and thus 30 force the sectors home as above described and as illustrated in Fig. 4. Thus the refaced die sectors assembly will draw a bar of the same cross-sectional dimensions as was the case originally.

A die assembly as described and illustrated 35 above in addition to accurately and uniformly drawing bars and being capable of being refaced to draw bars of the same cross-sectional dimensions possesses the advantages that both initially and when refaced the sectors can be ground independently in a suitable grinding and gauging machine or machines so that all sectors are identical.

Although I have described and illustrated my die assembly as being applicable for drawing hexagon bars by changing the number and/or the 45 conformation of the sectors, bars of an infinite variety of polygonal shapes can be drawn.

What I claim as my invention is:

1. A die for cold drawing steel bars into polygon shapes comprising a housing, a single die sector holding ring inserted into the housing, a plurality of substantially sector shaped portions assembled in the die sector holding ring with their radial faces abutting each other and their bar engaging faces forming an opening of the polygonal shape of the bar to be drawn therethrough, said die sector holding ring being operable longitudinally with respect to such sector shaped portions, and retaining means adjustably disposed in the housing and engaging the die sector holding 60 ring.

2. A die for cold drawing steel bars into polygonal shapes comprising a housing, a die sector holding ring, a plurality of die sectors each having an arcuate outer face, radially extending side 65 faces and an inner bar drawing face, said die sectors being assembled in the die sector holding ring with their radial faces in abutting relation, their bar drawing faces forming an opening of the polygonal shape of the bar to be drawn there- 70 through and their arcuate outer faces engaging the interior of the die sector holding ring, said die sector holding ring being inserted into the interior of the housing, and means for removably retaining the die sector holding ring and die sectors in 75 the housing.

3. A die as claimed in claim 2 wherein means is provided in the housing for engaging the die sectors and forcing them into intimate contact with each other upon the retaining means being actuated. 5

4. A die as claimed in claim 2 wherein the means for removably retaining the die sector holding ring and die sectors in the housing comprises a retaining ring threaded into the interior of the housing and engaging the die sector holding ring. 10

5. A die as claimed in claim 2 wherein a plate is disposed in the housing engaging the rear faces of the die sectors and forcing them forwardly into intimate contact with each other upon 15 the retaining means being actuated.

6. A die for cold drawing steel bars into polygonal shapes comprising a housing having a cylindrical interior open at its forward or bar entering end and its closed rear end having an axial bar receiving orifice therethrough, a cylindrical die sector holding ring disposed in the cylindrical interior of the housing and having a concentric truncated conical interior with its smaller end directed towards the forward end of the housing, 20 a plurality of substantially sector shaped portions disposed in the truncated conical interior of the die sector holding ring with their radial faces in abutment with each other and their bar engaging or drawing faces forming an opening of the polygonal shape of the bar to be drawn, said sector shaped portions having arcuate outer faces inclined inwardly in a longitudinal direction from forward to rear end to correspond with the inclination of the truncated conical interior of the die sector holding ring and engageable therewith, and adjustable and removable means closing the open forward end of the housing and engageable with the die sector holding ring for retaining the latter and the sector portions therein in position. 25

7. A die as claimed in claim 6 wherein the adjustable and removable means comprises a retaining ring threaded into the open forward end of the housing and engageable with the die sector holding ring. 30

8. A die as claimed in claim 6 wherein a circular plate having a boss insertable into the orifice in the rear end of the housing is interposed between the latter and the rear ends of the sector shaped die portions, said plate being of a 35 diameter capable of entering the truncated conical interior of the die sector holding ring.

9. A die for cold drawing steel bars into polygonal shapes comprising a housing having a cylindrical interior open at its forward or bar entering end and its closed rear end having an axial bar receiving orifice therethrough, a cylindrical die sector holding ring disposed in the cylindrical interior of the housing and having a concentric truncated conical interior with its smaller end 40 directed towards the forward end of the housing, a plurality of substantially sector shaped portions disposed in the truncated conical interior of the die sector holding ring with their radial faces in abutment with each other and their bar engaging or drawing faces forming an opening of the polygonal shape of the bar to be drawn, said sector shaped portions having arcuate outer faces inclined inwardly in a longitudinal direction from forward to rear end to correspond with the inclination of the truncated conical interior of the die sector holding ring and engageable therewith, a circular plate disposed 45

the sector shaped portions and of a diameter capable of entering the truncated conical interior of the die sector holding ring, and a retaining ring threaded into the forward end of the housing and engaging the die sector holding ring.

10. In a die for cold drawing steel bars into polygon shapes, the combination with a die sector holding ring having its interior tapering inwardly towards its bar entering face, of a plurality of die sectors, each having an arcuate outer face of substantially the radius of the interior

of the die sector holding ring and tapering correspondingly thereto, radially extending side faces, and an inner bar drawing face, said die sectors being assembled in the die sector holding ring with their radial faces in abutment with each other, their bar drawing faces forming an opening of the polygonal shape of the bar to be drawn therethrough and their arcuate outer faces engaging the interior of the die sector holding ring.
